UNITED STATES PATENT OFFICE.

HEINRICH BAUMHAUER, OF CHARLOTTENBURG, NEAR BERLIN, GERMANY, ASSIGNOR,
BY MESNE ASSIGNMENTS, TO PATENT-TREUHAND-GESELLSCHAFT FUER ELEC-
TRISCHE GLUHLAMPEN, M. B. H., OF BERLIN, GERMANY, A CORPORATION OF
GERMANY.

ELECTRIC GLOW-LAMP.

1,401,510.

Specification of Letters Patent. Patented Dec. 27, 1921.

No Drawing.

Application filed November 13, 1917. Serial No. 201,880.

To all whom it may concern:

Be it known that I, HEINRICH BAUMHAUER, a German citizen, and resident of Charlottenburg, near Berlin, Germany, have 5 invented certain new and useful Improvements in Electric Glow-Lamps, of which the following is a specification.

My invention relates to electric glow lamps and more especially to carbon filament 15 lamps, and its particular object is a glow lamp of this type having a longer life and a higher load capacity than the carbon filament lamps heretofore devised.

According to my invention the lamp is 15 filled with rare gases such as argon, neon, helium, crypton, xenon in a state of high purity.

It is well known that the life of a carbon filament can be increased considerably by 20 filling the lamp with a suitable gas such as for instance nitrogen or carbonic acid. Provided that the gas pressure was kept sufficiently high a considerable diminution of the vaporization of carbon and a correspondingly longer life of the filament is obtained, 25 the nitrogen or other gas used being practically inert. On the other hand by sacrificing the longer life it was possible, in lamps of that kind, to place the filament under an increased load and to thus obtain a superior 30 economy.

If nitrogen and the like were replaced by one of the rare gases mentioned above, no particular difference could at first be ascertained with regard to the carbon filament. 35 In both cases a limit was soon reached where the vaporization of the carbon and the destruction of the filament could not be prevented any more by the gases placed under 40 reasonable pressure. It is true that the so called concentrated disposition of the filament in an atmosphere of rare gases furnishes very remarkable results in another direction. Thus for instance the life of a 45 lamp consuming about one and a half Watt per candle can be brought up to several hundred hours and the length of the filament can be kept so low as to impart to it very useful mechanical properties. This was more than 50 could be expected from the carbon filament as such, but it seemed at the same time that there were no means for exceeding the lim-

its put to the carbon by its nature, its vapor tension and its inherent disintegration.

It is further known that the rare gases 5 employed for filling the lamps were always mixed with small quantities of nitrogen and other substances, and there were no methods known for totally getting rid of these admixtures. Moreover, so far as I am aware, 60 the art up to date has not recognized that these remaining nitrogen admixtures would have any detrimental effect upon the function of the lamp.

In the meantime methods have been found 65 for obtaining commercial quantities of the rare gases, and quite especially argon, in a state of almost perfect purity. My invention consists in using such substantially pure gases for filling electric glow lamps, 70 as I have ascertained that when the remainder of nitrogen and other impurities is removed so far that they can no more be traced by the ordinary spectroscopic methods, the purified atmosphere of rare gases entirely 75 changes the behavior of the carbon, its life as well as the load-capacity of the filament being increased quite materially.

I cannot undertake at present to definitely state the reasons for this, but I believe that 80 there are two circumstances coöperating with each other which were practically unknown up to date. On the one hand the natural vapor tension of carbon of any kind is apparently far lower than could be supposed 85 according to prior experiments. On the other hand I believe that although nitrogen is practically inert at somewhat lower temperatures, its affinity toward carbon is increased to an extraordinary extent as soon as 90 a certain limit of temperature is exceeded, very small quantities of nitrogen then exerting a very obnoxious effect, the more so, as this effect does not enter into appearance by the fact that the small quantities of nitrogen 95 combine with the carbon, but by the fact, that these combinations are permanently decomposed in other places, carbon being deposited at the same time, so that one and the same small quantity of nitrogen will then 100 exert its obnoxious effect repeatedly.

Of course, if to the purified rare gases other substances are admixed, such as for instance a certain quantity of mercury va-

por, which do not act in a manner similar to nitrogen, the favorable effect of the pure atmosphere of rare gases is not impaired thereby.

5 I claim:

1. An electric carbon filament glow lamp having its filament surrounded by a rare gas substantially free of nitrogen.

10 2. An electric carbon filament glow lamp having its filament surrounded by pure argon substantially free of nitrogen.

3. In a glow lamp in combination a lamp globe, a carbon filament inclosed within said globe and an atmosphere of pure rare gases

substantially free of nitrogen surrounding 15 said filament.

4. In a glow lamp in combination a lamp globe, a carbon filament inclosed within said globe and an atmosphere of pure argon substantially free of nitrogen surrounding said 20 filament.

In testimony whereof I affix my signature in presence of two witnesses.

HEINRICH BAUMHAUER
